R. C. LAPE

CALENDAR

Filed Jan. 16, 1924

UNITED STATES PATENT OFFICE.

RUSSELL C. LAPE, OF COLUMBUS, OHIO.

CALENDAR.

Application filed January 16, 1924. Serial No. 686,570.

To all whom it may concern:

Be it known that I, RUSSELL C. LAPE, a citizen of the United States of America, residing at Columbus, in the county of Franklin and State of Ohio, have invented certain new and useful Improvements in Calendars, of which the following is a specification.

My present invention relates generally to 10 calendars and more particularly to that type of calendar employing a movable indicator, my object being the provision of a neat, effective and compact device capable of use in the home and also adapted to be carried in 15 the pocket, and a further object is the provision of a calendar of the movable indicator type which is capable of ready manipulation and necessitates but little instruction for its effective use.

20 A still further object of my invention is the provision of a calendar of the above type by means of which dates over a period of two years may be readily ascertained, which may be cheaply constructed and especially 25 adapted for advertising purposes.

In the accompanying drawing which illustrates my present invention and forms a part of this specification,

Figure 1 is a face view of the complete 30 calendar,

Figure 2 is a side elevation thereof, the holder being shown in dotted lines in its folded position for pocket use,

Figure 3 is a central longitudinal section 35 taken partly through the complete calendar,

Figure 4 is a face view of a portion of the holder, with the indicator removed, and

Figure 5 is a face view of a portion of the sliding indicator.

40 Referring now to these figures my invention proposes a calendar including an elongated rectangular holder 10 having longitudinally along its opposite side edges lists of week days imprinted thereon as indicated at 11 and 12, the several week day indications being preferably abbreviated as shown and disposed in the lists transversely with respect to the longitudinal axis of the holder so as to be conveniently read when 45 the holder is supported with its longitudinal axis upright.

It will also be noted that the holder is of such length as to provide considerable spaces 50 13 and 14 at the upper and lower ends of

its lists of week day indications 11 and 12, 55 of which the upper space 13 may be utilized for the imprinting of directions for the use of the calendar and the lower space 14 may be utilized to receive suitable advertisements, a holder of considerable length being required as hereinafter made plain where, as in the present instance, folding is contemplated in order that the calendar as a whole may be carried in the pocket.

The imprinting of the two lists of week 60 days indicated at 11 and 12 leaves a central space 15 along the upper portion of which a tongue 16 freely depends between the lists 11 and 12, this tongue being securely connected at its upper end to the upper end 65 of the holder 10 by means, preferably in the nature of a grommet or eyelet 17 which thus adapts the calendar as a whole to be fixed by a nail, tack, screw or other fastening member upon a wall or other supporting 70 surface. Along the tongue at spaced points are transversely arranged the imprinted designations of the several months of the year as indicated at 18, some of which are repeated as in the case of the week day lists 80 11 and 12, for obvious purposes, this tongue forming a guide for the sliding indicator 19 whose upper body portion has lengthwise spaced vertical slots 20 through which the tongue 16 is passed so as to expose a portion 85 of the tongue 16 between the slots 20.

The sliding indicator 19 has transverse indicating lines 21 in the same plane upon opposite sides of the exposed portion of the tongue 16 and thus between the planes of 90 the slots 20 and the sliding indicator is further provided with a depending tongue 22 having a lengthwise series of divisions separated by spacing lines 23, each division having a series of numerals 24 constituting indications of the days of the months, there being seven divisions on the tongue 22, each starting with a different numeral from one to seven inclusive and it will be noted that each division has numerals increasing by 95 seven between its starting numeral and the numeral thirty-one.

Thus by shifting the sliding indicator 10 up or down on the tongue 16 until its indicating lines 21 register with the month 100 in which the desired week day or monthly date occurs, the tongue 22 of the sliding indicator will cooperate with the lists 11

and 12 so that either the day of the week or the date of the month may be readily determined, it being observed that reference is made to the numerical divisions of the tongue 22 and the left hand week day list 11 of the holder in one year while reference is made to the numerical divisions of the tongue 22 and the right hand list 12 for the next succeeding year.

10 It is obvious from this that the calendar is thus adapted for a two year period, the yearly designations being preferably imprinted as at 25 and 26 upon the lower portion of the body of the sliding indicator 19 respectively above the week day lists 11 and 12 of the holder.

It is also obvious from an inspection of Figure 1 that the tongue 22 of the sliding indicator overlies that portion of the tongue 16 of the holder extending below the body of the indicator and that by providing the lower end of the tongue 16 with a suitable stop member as for instance a grommet or eyelet 27, the slide will be prevented from complete withdrawal or accidental displacement from the tongue 16.

It will also be observed that by sliding the indicator 19 upwardly to the upper limit of its movement on the tongue 16, provision is made for holding the holder 10 lengthwise as indicated in dotted lines in Figure 2 and for the purpose of securing the holder when so folded in order that it may be readily adapted to pocket use, the lower end of the holder 10 has secured thereto a central endwise projecting tab 28 which may in the folded position of the holder be extended around the upper end thereof so that the free end of the tab may be projected through a transverse slot 29 with which the holder is provided adjacent to its upper end, the tab when extended through this slot 29 thus serving to detachably hold the calendar in folded position for carrying in the pocket. 45 It is obvious that when so carried the folded portions of the holder 10 serve to protect the slide with its tongue as well as the tongue 16.

The calendar as illustrated is for the years 50 1924 and 1925 but obviously it can be made for any two, or possibly more years by the proper working out and arrangement of the printing matter pertaining to dates, days of each week etc.

55 The name or other identifying matter concerning the person of the user may be placed on the holder beneath the tongues, if desired.

I claim:

60 1. A calendar of the present type including a holder having imprinted upon its surface designations of the week days arranged in a series and also having a tongue fixed at one end to the holder and extending freely 65 along the said week day designations, the

said tongue being provided with a list of the months, and a slide associated with the said tongue, through which a portion of the tongue is exposed whereby the slide may be moved opposite to a selected month, said 70 slide having a tongue overlying the tongue of the holder and provided with a series of divisions each division bearing selected numerical dates arranged to be positioned opposite the week day designations of the 75 holder.

2. A calendar of the character described including an elongated holder adapted to be folded upon itself and having means to detachably support the same in folded position, said holder having upon its face a longitudinally arranged list of week day designations, a tongue connected to the holder and extending along the said series of week day designations, having thereon lengthwise 85 spaced designations of the months, and a slide movably associated with said tongue and through which a portion of the tongue is exposed to permit the slide to be moved opposite a selected month designation of 90 the tongue, said slide having a reduced extending tongue overlying the tongue of the holder and provided with a series of divisions, each division having a series of tab designations to cooperate with the day 95 designations of the holder, said slide being of a relative length permitting the holder to be folded as described.

3. A calendar including a holder of elongated rectangular form, a tongue secured at 100 one end to one end of the holder and extending lengthwise along a portion of the length of the holder, a slide having spaced transverse slots through which the tongue is extended so as to expose a portion of the 105 tongue between the slots, and also having a tongue overlying the tongue of the holder, said holder and said tongues being respectively provided with day, month and date 110 designations adapted for cooperation with one another, the holder being foldable upon itself when the slide is shifted to the limit of its movement on the holder tongue toward one end of the holder whereby to enclose the tongues and the indicator between 115 its folded portions.

4. A calendar including a holder of elongated rectangular form, a tongue secured at one end to one end of the holder and extending lengthwise along a portion of the length of the holder, a slide having spaced transverse slots through which the tongue is extended so as to expose a portion of the tongue between the slots, and also having a tongue 125 overlying the tongue of the holder, said holder and said tongues being respectively provided with day, month and date designations adapted for cooperation with one another, the holder being foldable upon itself when the slide is shifted to the limit of its 130

movement on the holder tongue toward one end of the holder whereby to enclose the tongues and the indicator between its folded portions, one end of said holder having a tab bendable around the other end

to its opposite end to receive the free end of the tab whereby to secure the holder in folded position.

10

In testimony whereof I have affixed my signature.

RUSSELL C. LAPE.
